DROP BOTTOM MINE CAR

William F. Dietrichson, Berwick, Pa., assignor to
American Car and Foundry Company, New
York, N. Y., a corporation of New Jersey

Application July 17, 1936, Serial No. 91,035

11 Claims. (Cl. 105—364)

This invention relates to mine cars of the drop-bottom type in general and in particular to automatic drop bottom cars wherein the transversely hung doors move longitudinally of the car.

5 Previous cars having the free edge of one door resting on the hinge edge of the following door have been constructed, but in these cars the hinge rod or a projecting portion of the door plate formed an eccentric which permitted only a small 10 bearing area between doors and any distortion of the doors was liable to cause a premature discharge of the lading. It is an object, therefore, of this invention to provide a door arrangement such that the doors may have a large amount 15 of overlap when in the closed position.

Another object of the invention is the provision of a drop bottom car having doors supported entirely by rugged, laterally movable hinge rods.

20 A further object of the invention is the provision of an improved traversable hinge rod support and protecting housing.

A still further object of the invention is the provision of an improved traversable hinge rod support which is protected from the lading at 25 all times.

These and other objects of the invention will be apparent to one skilled in the art from a study of the following description and accompanying drawings, in which:

Figure 1 is a side view of approximately one-half of the car, parts being broken away to more fully disclose the latch and hinge members;

Fig. 2 is a sectional view of the remaining portion of the car shown in Fig. 1;

Fig. 3 is a plan view of a portion of the car;

Fig. 4 is an enlarged sectional view showing more clearly the traversable hinge rod support;

Fig. 5 is a plan view of the portion of the car 40 shown in Fig. 4 with parts in section to disclose the hinge rod support;

Fig. 6 is a sectional view taken on line 6—6 of Fig. 5;

Fig. 7 is a sectional view showing the relation of the protecting housing and hinge rod support castings, the door being shown in fully open position;

Fig. 8 is a sectional view similar to Fig. 4 but 50 showing a slightly modified form of construction;

Fig. 9 is a plan view partly in section of the modified form shown in Fig. 8;

Fig. 10 is a sectional view taken on line 10—10 55 of Fig. 9, and

Fig. 11 is a sectional view similar to Fig. 10 but showing a further modification.

Referring now to the drawings in detail, it is seen that the car shown is of conventional contour and design with the exception of the door 5 mounting and operation. In the car shown the bulb angle side sills 2 are mounted upon axles 4 by means of bearings 6 and these sills are joined at their ends by channel end sills 8. The end sills have attached thereto any approved type of 10 draw head 10 and bumper 12, the details of which need not be described since they form no part of the present invention. End walls 14 are attached to the end sills and to the flare side walls 16 carried by the bulb angle side sills. The side 15 walls have hoods 18 pressed therein to accommodate the upper portions of the car supporting wheels 20 mounted upon the axles as is customary. Suitable axle deflectors 22 extend between the 20 inner faces of the side sills to which they are welded as at W. Side wall braces 24 stiffen the side walls, while the rear end wall is provided with a latch mechanism L formed in part of a hook 26 which engages the rear or free portion 28 of the rear door 30.

The car bottom is preferably formed of three doors, namely, the rear door 30, intermediate door 32 and front door 34, the latter of which is pivoted by hinge members 36 to the front end sill. The front edges of the rear and intermediate 30 doors are hinged to the car in the improved manner now to be described with special reference to Figs. 1-7 inclusive.

The forward edge of the rear and intermediate doors is rolled over as at 38 to non-rotatably embrace hinge rod 40 upon the ends of which are rigidly secured the roller member 41 having teeth 42 adapted to inter-engage with the spaced bars 43, 44 and 45. The spaced bars are integral with the sill engaging flanges 46 and 48, the latter of which is also joined to the bars by extensions 49. The inner ends of the bars are joined by wall 50 thus forming an extremely strong traversable hinge rod support which is securely fastened to the bulb angle flange and web by rivets or other means 52. In order to retain the door in position as well as to exclude lading a cast housing is provided having a sill securing flange 54 from which extends ledge 55 braced by 50 gussets 56. The ledge terminates in a downwardly directed flange 56, a portion of which is cut away to straddle the pivot support and permit the traversing movement of the hinge rod. It is thus seen that it is almost impossible for lading 55

to get upon the supporting bars of the traversable support, particularly since the door flange 59 is turned upwardly and will cover the opening or cut out portion in the hood member.

5 Referring now in particular to Figs. 8-10 inclusive in which a slight modification has been disclosed and using wherever possible the same numerals as were used in connection with Figs. 1-7 inclusive. The door retaining and protecting housing has been enlarged in order to permit a plate 60 to be moved therein by the door. Plate 60 is carried upon collar 62 mounted upon the hinge rod and is of such a size as to overlap the downwardly directed flange 58 and completely 10 cover the opening or cut-out portion at all times, whether the door be closed or open.

In Fig. 11 the construction shown in Figs. 8-10 is modified in that the roller member has been formed with a circular portion 64 adapted to 20 roll upon the wall 50 and thus assist to a major extent the bars in the support of the doors and lading.

In each of these modifications it is seen that the free edge 66 of each preceding door rests 25 upon the rear edge of the succeeding door directly above the hinge rod and that the area of contact between the doors is of a substantial amount and located approximately at right angles to the direction of swinging movement of the door. Attention is also directed to the fact that the bar 43 which must support the load during the transporting period is considerably heavier than the other bars which need support only the door during 30 its traverse of the hinge support.

35 The operation of the doors is as follows, and assuming the doors to be in the closed position. Upon release of the hook 26 by any suitable means, the door 30 will drop swinging about its axis causing the toothed roller to leave bar 43 and successively engage the bars 44 and 45. The hinge rod is thus made to traverse the hinge rod support and in doing so it will move rearwardly from beneath the edge 66 of the preceding door 32 permitting it to drop and in the manner just 40 described this door will release the door 34. In the closing the movement is simply reversed and the door 34 is raised and held raised until the door 32 has been raised and shifted beneath the edge 66 of door 34.

50 The operation of the form shown in Figs. 8-10 is identical with that just described but in this form the plate 60 is shifted with the hinge rod and will completely cover the opening in flange 58 at all times, thus insuring the protection of the toothed roller and bars from the lading. In the form shown in Fig. 11 the only difference in operation is that the major portion of the door load is carried by the shoulder 64 rolling on the 55 wall 50 and not by the bars directly.

It is obvious that even though lading should sift into the housing, it can immediately escape between the bars of the traversable hinge support without causing any damage to the bars or the 60 toothed roller. The traversable hinge support may be properly considered as an open toothed rack to distinguish from the usual type of rack in which the bases of the teeth are joined together.

70 While the door hinging means has been described more or less in detail, it is obvious that various modifications will suggest themselves to persons skilled in the art and all such modifications are contemplated as fall within the scope of 75 the following claims.

What is claimed is:

1. In a mine car for the transport of lading, sills, axles and axle bearings supporting the sills, a dumping door, a hinge rod for said door, supporting brackets for said hinge rod secured to the sills independently of the axle bearings, interengaging means on said hinge rod and brackets for bodily shifting the door during the opening thereof, a second dumping door hinged to the car and having the free edge thereof normally resting directly upon said first named door above the hinge rod and above the horizontal plane through the lower portion of the axles, said second named door being free to open after the bodily shifting of the first named door. 15

2. In a mine car for the transport of lading, sills, axles and axle bearings supporting the sills, a dumping door, a hinge rod for said door, brackets secured to the sills adjacent an axle for supporting said hinge rod, interengaging means on said hinge rod and brackets for bodily shifting the door toward the adjacent axle during the opening thereof, housings secured to the sills and protecting said interengaging means from the lading, and a second dumping door hinged to the car and having the free edge thereof normally resting directly upon said first named door above the hinge rod and substantially in horizontal alignment with the axles, said second named door being free to open after the bodily shifting of the first named door. 25

3. In a mine car for the transport of lading, sills, axles and axle bearings supporting the sills, a dumping door, a traversing hinge rod for said door, traversable supporting brackets secured to the sills adjacent an axle for supporting said hinge rod, interengaging means on said hinge rod and brackets for bodily shifting the door during the opening thereof, a second dumping door hinged to the car and having the free edge thereof supported solely by said hinge rod in substantial horizontal alignment with the axles, said second named door being free to open after the bodily shifting of the first named door. 35

4. In a mine car for the transport of lading, sills, axles and axle bearings supporting the sills, a dumping door, a traversing hinge rod for said door, traversable supporting brackets secured to the sills for supporting said hinge rod substantially in horizontal alignment with the axles, interengaging means on said hinge rod and brackets for bodily shifting the door during the opening thereof, a housing protecting said interengaging means from the lading, and a second dumping door hinged to the car and having the free edge thereof supported solely by said hinge rod, said second named door being free to open after the bodily shifting of the first named door. 40 50

5. A traversable hinge rod supporting bracket for mine cars having flanged side sills comprising, a vertical flange for attachment to the sill web, a horizontally disposed flange for attachment to the sill flange, bars projecting laterally inward from said vertical flange for supporting a hinge rod, continuations of said bars being joined to said horizontally disposed flange for bracing the bracket flanges. 55 60

6. A door hinge assembly for mine cars adapted to carry lading comprising a traversable hinge rod supporting bracket having substantially vertical and horizontal flanges for attachment to the car sills, bars projecting laterally inward from said vertical flange for supporting a hinge rod, a wall joining the inner edges of said bars, and 70 75 80 85 90 95

a hinge rod having projections interengaging with said bars between said wall and vertical flange to cause shifting of said rod during rotation thereof.

5. 7. A door hinge assembly for mine cars adapted to carry lading comprising, a traversable hinge rod supporting bracket having substantially vertical and horizontal flanges for attachment to the car sills, bars projecting laterally inward from 10 said vertical flange for supporting a hinge rod, a wall joining the inner edges of said bars, and a hinge rod having projections interengaging with said bars between said wall and vertical flange to cause shifting of said rod during rotation 15 thereof, and a housing secured to the sills and protecting said bars and hinge rod projections from the lading.

8. A door hinge assembly for mine cars adapted to carry lading comprising, a traversable hinge 20 rod supporting bracket having substantially vertical and horizontal flanges for attachment to the car sills, bars projecting laterally inward from said vertical flange for supporting a hinge rod, a hinge rod having projections interengaging with 25 said bars to cause shifting of said rod during rotation thereof, and a housing secured to the sills and protecting said bars and hinge rod projections from the lading, said housing being formed with a slot through which the rod projects thereby permitting shifting of the hinge rod.

9. A door hinge assembly for mine cars adapted to carry lading comprising, a traversable hinge rod supporting bracket having substantially vertical and horizontal flanges for attachment to the 30 car sills, bars projecting laterally inward from said vertical flange for supporting a hinge rod, a hinge rod having projections interengaging with said bars to cause shifting of said rod during rotation thereof, a housing secured to the sills

and protecting said bars and hinge rod projections from the lading and said housing being formed with a slot permitting shifting of the hinge rod and a slide plate carried by said hinge rod adapted to maintain the slot closed to prevent 5 entrance of lading.

10. A door hinge assembly for mine cars adapted to carry lading comprising, a traversable hinge rod supporting bracket having substantially vertical and horizontal flanges for attachment to the car sills, bars projecting laterally inward from 10 said vertical flange for supporting a hinge rod, a hinge rod having projections interengaging with said bars to cause shifting of said rod during rotation thereof, and a housing secured to the sills and protecting said bars and hinge rod projections from the lading and said housing being formed with a slot permitting shifting 15 of the hinge rod, and a slide plate carried by said hinge rod adapted to maintain the slot closed, said slide plate being of sufficient length to maintain the slot closed at all times to prevent entrance of lading.

11. A door hinge assembly for mine cars adapted to carry lading comprising, traversable hinge rod supporting brackets secured to the car sills, bars formed on said brackets and projecting laterally inward therefrom to support a hinge rod, a hinge rod having projections on its ends interengaging with said bars to cause shifting of said rod during rotation thereof, and housings secured to the sills and protecting said bars and hinge rod projections from the lading, each of said brackets being provided with a wall joining the inner edges of the bars and adapted to directly support the hinge rod whereby said bars are relieved of load strain.

WILLIAM F. DIETRICHSON.
